UNITED STATES PATENT OFFICE.

WARREN BARNHART, OF CHICAGO, ILLINOIS, ASSIGNOR TO ARTHUR M.
AND ALSON E. BARNHART, OF SAME PLACE.

DESIGN FOR PRINTING-TYPE.

SPECIFICATION forming part of Design No. 16,490, dated January 26, 1886.

Application filed July 27, 1885. Serial No. 172,825. Term of patent 14 years.

To all whom it may concern:

Be it known that I, WARREN BARNHART, a citizen of the United States, residing in the city of Chicago, county of Cook, and State of Illinois, have invented and produced a new and original Design for a Font of Printing-Types, of which the accompanying impression is an exact representation, and is a part of this specification.

- 10 The character of the design is a semi-grotesque Gothic condensed of medium weight; and it consists of capitals, figures, points, and lower-case, all the lines being of uniform weight, excepting where they taper.
- 15 Each of the letters, excepting capital and lower-case I, is formed by a combination of angles, so as to produce a new effect. Capitals B, C, D, E, F, G, O, P, Q, R, T, and U are square at top and bottom, inside and out-side, excepting at the corners, either at top and bottom, or at both. The same features are also shown in all the numerals, excepting figures 1, 4, and 7. Lower-case b, h, m, n, p, and r are mitered where the short horizontal stroke

on the right side of the letter connects with the long perpendicular stroke. The same feature is also shown in lower-case d, g, and q, the miter being on the opposite or left side of the perpendicular stroke. This feature is again shown in lower-case u and y at the bottom. Three final lower-case letters, h, m, and n, are shown, which are the same in construction as those before mentioned, excepting the stroke at the right side curves inward and graduates to a point below the line.

Having now described my design, what I claim as new is—

The design for a font of printing types, the character of which is a semi grotesque Gothic condensed, all the letters showing vertical, horizontal, diagonal, or curved lines of uniform weight, excepting where they taper or are mitered, as shown and described.

WARREN BARNHART.
